UNITED STATES PATENT OFFICE.

JOHN NELSON, OF NEWTON, IOWA, ASSIGNOR TO AUTOMATIC ELECTRIC WASHER CO.,
OF NEWTON, IOWA.

HYDRODISK FOR WASHING MACHINES.

Application filed December 28, 1923. Serial No. 683,123.

This invention relates to a hydro-disk for washing machines preferably of that type in which alternate rotary motion is imparted to the agitating and washing element.

5 The invention comprises an agitating disk so constructed that it will float without a vacuum over the water in the wash tub during its rotation and the action of which is such that an inverted whirlpool will result 10 so that the clothes will be more effectively agitated and cleansed.

The invention comprises the novel structure and combination hereinafter described and more particularly pointed out and defined in the appended claims.

In the accompanying drawings which illustrate a preferred form of this invention and in which similar reference numerals refer to similar features in the different 20 views.

Figure 1 is a bottom plan view of the hydro disk.

Figure 2 is an elevational view of the disk.

25 Figure 3 is a fragmentary sectional view of the disk at one of the pockets.

Figure 4 is a sectional view through a washing machine illustrating the floating characteristics of the disk.

30 As shown on the drawings:

Referring to the drawings which illustrate one embodiment of this invention there is shown a metal disk 1 preferably made of some light metal as aluminum. This disk 35 though heavier than water has a contour upon its lower surface that causes it to substantially float upon the water and clothes during the rotation thereof. This contour is preferably in the form of downwardly extending converging parts or humps, the bottoms of which slope downwardly toward the outer circumference of the disk. In the present instance the disk is shown as formed with downwardly and radially extending pockets 2; the side walls of which converge 45

toward each other, wedge-like in formation and the bottoms slope downwardly from their inner ends toward the outer periphery of the disk. A series of apertures or perforations 3 are formed in the bottom of each disk to provide communication between the water that usually enters the pockets and the water in the wash tub so that the disk 50 will not be appreciably weighted thereby.

55 The outer ends of the pockets are substan-

tially closed as indicated at 4. A concave or other recess 5 however is formed in the upper portion of each end 4 to allow the water in the pockets to be cascaded outwardly. While any suitable number of such 60 radial extending pockets may be formed in each disk, in the present instance I have shown five which are equally spaced apart.

The central part of the disk is formed with a hub 6 through which a polygonal 65 aperture 7 extends.

In Figure 4 I have shown the disk 1 in connection with a washing machine which consists of a cylindrical container. A polygonal rod 8 is attached in the aperture of 70 the disk 1 and slidably extends through a bearing in the cover of the tub, and through a gear 9 confined against vertical movement. The disk 1 can accordingly rise and fall on account of the vertically slidable mounting 75 of the shaft 8. A segmental rack 10 or any other suitable mechanism may be used for imparting alternate rotary movement to the rod 8.

While the weight of the hydro-disk 1 is 80 heavier than water, it will nevertheless operate over the surface of the water in the tub on account of the wedge shaped and sloping pockets or depressions which tend to raise the disk out of the water during rotation thereof. In other words, the disk 1 has a tendency to float over the water during the operation thereof; the humps being in 85 the water and also serving to rub the clothes.

During the operation of the washing machine, the rotation of the disk will force the clothes and water outwardly and downwardly and at the same time rubbing the same, the clothes and water rising up in the center to take the place of the displaced 90 clothes and water. This action may be appropriately described as an inverted whirlpool. There will hence be an effective agitation of the clothes to properly cleanse the same.

I am aware that many changes may be made, and numerous details of construction may be varied through a wide range without departing from the principles of this invention, and I therefore do not purpose 105 limiting the patent granted hereon, otherwise than necessitated by the prior art.

I claim as my invention:

1. In a washing machine an agitating disk of greater specific gravity than water 110

having radially extending and downwardly converging pockets, said pockets having outwardly and downwardly sloping perforated bottoms, and means for supporting said disk for rotary and vertical movement.

2. In a washing machine, a hydro disk having radially extending and downwardly converging perforated humps upon its lower surface, said humps having downwardly and outwardly sloping bottom surfaces, and means for supporting said disk for vertical movement.

3. In a washing machine, a metal disk of greater specific gravity than water having radially extending pockets formed therein and opening upwardly whereby humps are provided upon the bottom of the disk, each pocket having downwardly converging walls and an outwardly and downwardly sloping perforated bottom, the outer end of each pocket having an upper arcuate recess for cascading the washing fluid from the pocket.

4. A hydro disk having radially extending humps upon its lower surface, each hump having downwardly extending and substantially converging side walls, and a downwardly and outwardly sloping bottom.

5. In combination with a tub of a washing machine adapted to contain a washing liquid, a dolly, means for oscillatably supporting said dolly within the tub, said means being constructed and arranged to permit the free vertical movement of said dolly in the tub, and said dolly being composed of material of greater specific gravity than the liquid in the tub and rendered vertically projectible to substantially a water surface position through relative co-action of the dolly and water content of the tub resulting from oscillating the dolly.

6. In a washing machine, in combination, a liquid container, a disk of greater specific gravity than a liquid content, including deflector means thereon, means for centering

and adjustably supporting said disk and means for reciprocating said supporting and centering means, whereby relative contact between the disk and water content during such reciprocation will cause said disk to be maintained substantially at the surface level of said liquid content.

7. In a washing machine, in combination, a liquid container, a disk of greater specific gravity than a liquid content, and including deflector means thereon, means for supporting the disk to facilitate vertical projection thereof and including means for effecting relative reciprocation as between the container and disk, whereby resistance between the disk and water content will cause the former to be vertically projected and sustained at substantially the level of the liquid in the container.

8. In a washing machine, in combination, a liquid container, a disk of greater specific gravity than a liquid content and including deflector members thereon, means for centering and adjustably supporting the disk, and means for effecting relative reciprocation as between the container and the disk to cause the latter to be sustained during such relative reciprocation at substantially the liquid content level.

9. In combination with the tub of a washing machine adapted to contain washing liquid, a dolly, means for oscillatably supporting said dolly within the tub, said means being constructed and arranged to permit the free vertical movement of said dolly in the tub, and said dolly being composed of material of greater specific gravity than the liquid in the tub and rendered vertically projectible upon its driving support by structural characteristics of said dolly through the oscillation thereof within a liquid tub content.

In testimony whereof I have hereunto subscribed my name.

JOHN NELSON.
